CLAIM

The ornamental design for a head plate for compaction drum, as shown and described.

DESCRIPTION

FIG. 1 is a perspective view of a head plate for compaction drum according to my new design;

FIG. 2 is a front view of a head plate for compaction drum according to my new design;

FIG. 3 is a rear view of a head plate for compaction drum according to my new design;

FIG. 4 is a left view of a head plate for compaction drum according to my new design;

FIG. 5 is a right view of a head plate for compaction drum according to my new design;

FIG. 6 is a top plan view of a head plate for compaction drum according to my new design; and,

FIG. 7 is a bottom view of a head plate for compaction drum according to my new design.
